(57) **CLAIM**

The ornamental design for a motor with controller for power steering, as shown and described.

DESCRIPTION

FIG. 1 is a front, top and left-side perspective view of a motor with controller for power steering showing our new design;

FIG. 2 is rear, top and left-side perspective view thereof; FIG. 3 is a front, bottom and right-side perspective view thereof;

FIG. 4 is a rear, bottom and left-side perspective view thereof;

FIG. 5 is a front elevational view thereof;

FIG. 6 is a rear elevational view thereof;

FIG. 7 is a left-side elevational view thereof;

FIG. 8 is a right-side elevational view thereof;

FIG. 9 is a top plan view thereof; and,

FIG. 10 is a bottom plan view thereof.

The broken lines in the drawings illustrate portions of the motor with controller for power steering that form no part of the claimed design.

1 Claim, 7 Drawing Sheets
